UNITED STATES PATENT OFFICE.

HARRY A. BECKER, OF SAN FRANCISCO, CALIFORNIA.

DOOR-BOLT.

1,374,275.

Specification of Letters Patent. Patented Apr. 12, 1921.

Application filed May 24, 1920. Serial No. 383,905.

To all whom it may concern:

Be it known that I, HARRY A. BECKER, a citizen of the United States, residing at San Francisco, in the county of San Francisco and State of California, have invented certain new and useful Improvements in Door-Bolts, of which the following is a specification, reference being had to the accompanying drawings.

10 This invention relates to door bolts and has for its object to provide a door bolt constructed to eliminate rattling of the bolt at all times.

Another object is to provide a door bolt 15 containing a novel latch pin which prevents vibration from unfastening the bolt.

Another object is to provide a door bolt having a latch pin which may be adjusted and then set by means of a set screw according to the amount of play that is in the door 20 on which the bolt is used.

A still further object of the invention is to provide a door bolt including a base, said base having a housing in which a locking 25 bolt is slidably disposed, a plate being engaged with the bottom of the base, and a latch pin threaded through the bolt and movable with the bolt in said housing, the end of the pin being adapted to frictionally engage the plate at certain times to prevent 30 movement of the bolt.

With these and other objects in view, the invention consists in the improved construction and arrangement of parts to be herein- 35 after described, fully claimed and illustrated in the accompanying drawings, in which:—

Figure 1 is a vertical elevation of a door bolt constructed in accordance with an embodiment of the invention,

Fig. 2 is a section taken on the line 2—2 of Fig. 1,

Fig. 3 is a plan view,

Fig. 4 is a plan view of the base showing 45 the frame, and

Fig. 5 is a detail view of the plate adapted to be disposed in the frame.

Referring to the drawings, 5 designates a base member including downwardly extending flanges 6, which coincide with the edges of the base. These flanges coöperate with each other to form a frame, the purpose of which will be hereinafter described. A plurality of openings 6^a are provided in the 55 base, for the reception of suitable fastening means. The longitudinal intermediate por-

tion of the base is extended upwardly to provide a housing 7, the intermediate portion of the housing 7 having its side portion enlarged as at 8, said enlarged portion 60 being segmental in cross section and merges with the top of the housing 7. The opposite side wall of the housing 7 is provided with a slot 9 corresponding in length to the enlarged portion 8. Recesses 10 are formed 65 in the top of the housing adjacent the enlarged portion 8, said recesses communicating with the slot 9.

The end portions 11 of the housing 7 serve as bearings to properly position a locking 70 bolt 12 which is slidably and rotatably mounted in the housing 7. This locking bolt is provided with a threaded opening 13 which extends laterally of the bolt and is disposed at the intermediate portion of said 75 bolt. A latch pin 14 is provided, the shank of said pin being threaded, while one end thereof is enlarged to provide a finger piece 15. The latch pin 14 is intended to be screwed into the opening 13 to the extent 80 desired, the projecting end of the shank being movable within the enlarged portion 8 of the housing. In this way, the bolt may be readily operated without danger of the projecting end interfering with the sliding 85 or rotating movement of the bolt. In order to permit the latch pin 14 to be adjusted and maintained in its adjusted position, a threaded opening 16 is provided in the bolt 12 and intersects the opening 13. A set 90 screw 17 is disposed in the opening 16 and is adapted to engage the threaded shank to prevent the latch pin from rotating of its own accord.

A plate 18 is intended to be disposed within the frame formed by the flanges 6 of the base 5. This plate is provided with openings 19 which register with the openings 6^a in the base plate 5, but are slightly larger than the openings 6^a so as to prevent the 100 screws or like fastening means from holding the plate rigid.

When the locking bolt is applied to a closure such as a door, the plate 18 is disposed in engagement with the door and the base 5 disposed over the same so as to conceal the plate within the frame carried by the base. Fastening means such as screws, nails, etc. are passed through the openings 6^a and registering openings 19 so as to 110 secure the base member to the door. The latch pin 14 is then screwed through the

bolt until the the end of the pin projects the desired extent. The bolt may then be moved through the housing, the projecting end of the latch pin moving within the enlarged portion 8. When the bolt reaches the limit of its movement, the latch pin is swung downwardly into one of the recesses 10, thereby causing the projecting end of its shank to frictionally engage the adjacent portion of the plate 18 which is thereby forced into engagement with the door and serves as a brake, which eliminates rattling of the bolt and prevents vibration from disengaging the latch pin from the recess 10 and accidentally unfastening the bolt. If desired, the set screw 17 may be loosened so that when the bolt reaches the limits of movement the latch pin 14 may be screwed through the opening into firm engagement with the plate 18 so as to lock the bolt. In view of this novel arrangement, it is impossible for anyone to tamper with the bolt from the opposite side of the door such as endeavoring to slide the bolt from its locking position to its open position, as the latch pin positively prevents any movement of the bolt 12 until said pin is unfastened by unscrewing the same so as to cause the pin 14 to disengage the plate 18. When used on a gate, it also prevents the gate from being opened from the outside by means of an implement such as a piece of wire engaged with the latch pin to disengage said pin from its recess 10, as the locking pin will not move from its position in said recess in view of the fact that it is disposed in binding engagement with the plate 18. The frame formed by the flanges 6 is of a depth sufficient to receive the plate 18. At the same time, the plate does not rattle but is supported by the fastening means that extend through the base. In this way, the portion of the plate that is engaged by the end of the pin 14 is forced toward the door and serves as a brake. It also prevents the end of the pin from marring the door.

This door bolt may be used for various purposes and will be found very useful as an anti-rattling device for windows and also as a lock for windows, for holding the same in its closed position and also in various adjusted positions by the formation of a keeper recess 20 in the sash. The conventional form of keeper K may also be employed in connection with this door bolt.

From the foregoing it will be readily seen that this invention provides a novel form of door bolt which prevents rattling, and accidental unlocking of the bolt and provides a simple and efficient mechanism for accomplishing this result.

What is claimed is:—

1. A door bolt comprising a base including a housing, a portion of said housing being enlarged, the portion of said housing opposite the enlarged portion being slotted, a locking bolt rotatably and slidably mounted in said housing, said bolt having a laterally extending threaded opening, and an adjustable latch pin extending through said opening and slidable through said slot and within said enlarged portion to prevent unobstructed movement of the locking bolt. 65

2. A door bolt comprising a base including a housing, said housing having a longitudinally extending slot, a bolt rotatably and slidably disposed within said housing, said bolt having a laterally extending opening, a latch pin extending through and beyond said opening, and means disposed beneath said housing in engagement with the base, said means being adapted to limit the rotary movement of the latch pin, to prevent movement of the bolt within the housing. 70 80

3. A door bolt comprising a base including a housing, said housing having an enlarged portion and a longitudinally extending slot, a bolt rotatably and slidably disposed within said housing, said bolt having a laterally extending opening, a latch pin extending through said opening, the end of said pin projecting beyond the edge of said opening, the projecting end of said pin being movable at all times within said enlarged portion of the housing, and means for preventing rotation of the latch pin within the bolt. 90 95

4. A door bolt comprising a base, flanges extending from the edges of said base to provide a frame, a plate disposed within said frame and coinciding with the base, a housing formed on said base remote from said frame, the intermediate side portion of said housing being enlarged, the opposite side portion of said housing having a longitudinal slot, the top of said housing adjacent said slidable portion having spaced recesses communicating with said slot, a locking bolt rotatably and slidably mounted in said housing, said bolt having a laterally extending threaded opening, a latch pin disposed in said opening, and having its end projecting beyond one side of the bolt into the enlarged portion of said housing and movable within said housing and through said slot, said latch pin being rotatable into binding engagement with the plate when the pin is disposed in one of said recesses. 100 105 110 115 120

In testimony whereof I hereunto affix my signature.

HARRY A. BECKER.
